(57) **CLAIM**

We claim the ornamental design for an internal plug of a planting system, as shown and described.

DESCRIPTION

FIG. 1 depicts a perspective view of a first embodiment of an internal plug of a planting system;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof;

FIG. 7 is a bottom plan view thereof;

FIG. 8 depicts a cut-away view thereof.

FIG. 9 depicts a perspective view of a second embodiment of an internal plug of a planting system;

FIG. 10 is a front elevational view thereof;

FIG. 11 is a rear elevational view thereof;

FIG. 12 is a side elevational view thereof;

FIG. 13 is an opposite side elevational view thereof;

FIG. 14 is a top plan view thereof;

FIG. 15 is a bottom plan view thereof; and,

FIG. 16 depicts a cut-away view thereof.
